UNITED STATES PATENT OFFICE.

FOREST CHENEY, OF GRAND RAPIDS, MICHIGAN, ASSIGNOR OF ONE-THIRD TO GEORGE HENRY BENT, OF CHICAGO, ILLINOIS.

DESIGN FOR A BELL FOR A BRASS-WIND INSTRUMENT.

55,149.

Specification for Design.

Patented May 18, 1920.

Application filed October 20, 1919. Serial No. 332,117. Term of patent 14 years.

To all whom it may concern:

Be it known that I, FOREST CHENEY, a citizen of the United States, and a resident of Grand Rapids and State of Michigan, have invented a new, original, and ornamental Design for Bells for Brass-Wind Instruments, of which the following is a full, clear, and exact specification.

The figure is a perspective view, in dotted lines, of a brass wind instrument, showing my new design for bells applied thereto in full lines.

I claim:

An ornamental design for a bell for a brass wind instrument as shown.

In witness whereof I have hereunto set my hand and affixed my seal, this tenth day of October, A. D. 1919.

FOREST CHENEY. [L. S.]
